Primary Examiner — John A Voytek(74) *Attorney, Agent, or Firm* — Hanley, Flight & Zimmerman, LLC(57) **CLAIM**

The ornamental design for a "wheel", as shown and described in FIGS. 1-3.

DESCRIPTION

FIG. 1 is a left, front perspective view of a wheel disclosed herein. The illustrated wheel includes tire threads having a chevron pattern.

FIG. 2 is a left side view of the wheel of FIG. 1; and, FIG. 3 is a front view of the wheel of FIG. 1. The rear view is a mirror image of the front view.

The features shown in broken lines form no part of the claimed design.

The lighter solid lines denote surfaces and contours. Line shading is not surface ornamentation.
